CLAIM

The ornamental design for a writing tablet as shown and described.

DESCRIPTION

FIG. 1 is a front perspective view of a writing tablet showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of an enclosed area of the writing tablet labeled 9 in FIG. 1;

FIG. 10 is an enlarged view of an enclosed area of the writing tablet labeled 10 in FIG. 2;

FIG. 11 is an enlarged view of an enclosed area of the writing tablet labeled 11 in FIG. 2;

FIG. 12 is an enlarged view of an enclosed area of the writing tablet labeled 12 in FIG. 4; and,

FIG. 13 is an enlarged view of an enclosed area of the writing tablet labeled 13 in FIG. 8.

The evenly-dashed broken lines illustrate portions of the writing tablet that form no part of the claimed design. The dash-dot broken lines enclosing portions of the writing tablet illustrated in enlargements in FIGS. 9-13 form no part of the claimed design.

1 Claim, 8 Drawing Sheets
